UNITED STATES PATENT OFFICE.

MADS M. LARSEN, OF COLTON, CALIFORNIA, ASSIGNOR OF ONE-FOURTH TO MICHAEL A. BAUSCH, OF COLTON, CALIFORNIA.

COLLAPSIBLE CAMP TABLE.

Application filed December 12, 1922. Serial No. 606,432.

To all whom it may concern:

Be it known that I, MADS M. LARSEN, a citizen of the United States, residing at Colton, in the county of San Bernardino and State of California, have invented new and useful Improvements in Collapsible Camp Tables, of which the following is a specification.

This invention relates to camping equipment and more particularly to a collapsible camp table and case.

It is an object of the present invention to provide a camp table and case of simple and substantial construction and embodying a plurality of separable, foldable top and leg forming elements, and to provide a case about and upon which the collapsed elements may be packed and wrapped. It is another object to provide a collapsible camping outfit in which the various elements are of inexpensive and light form of construction so as to enable the ready carrying of the same.

Other objects and advantages will be made manifest in the following specification of an embodiment of the invention illustrated in the accompanying drawings, wherein—

Figure 1 is a perspective of the collapsed, packed device.

Fig. 2 is a section and end elevation of the device.

Fig. 3 is a sectional view showing in detail a leg and brace fastening means.

Fig. 4 is a perspective showing the opening of the table-top-forming, foldable element of the device.

Fig. 5 is a plan of a fragment of one of the cross pieces showing an underneath face thereof with a leg socket mounted therein.

Fig. 6 is a sectional detail showing the mode of attaching a leg to the leg socket of a cross piece.

Fig. 7 shows a perspective leg and brace elements detached.

Fig. 8 is a perspective showing the set-up table stand with the collapsible top in form to be placed upon the table stand.

Fig. 9 is a perspective of the lunch box. The present camp kit includes a top form-

ing element consisting of a plurality of longitudinally extending slat-like sections 2 arranged in close folding relation and having the outer or top face covered with a sheet of flexible material, such as canvas 3, or other suitable material, one edge of which top cover 3 is shown as extended along a longitudinal edge of the top in the form of a flange 3^a, this being provided with suitable fastening devices, such as snap sockets 3^b. Preferably, the meeting edges of the slats 2 forming the top are hingedly connected as by simple hinges 4, and the slats are adapted to be folded as to each other to form a rectangular wrapper or box, as is clearly shown in section in Fig. 2, and in which condition the top flange 3^a is adapted to be fastened to the contiguous buttons 3^c.

The foldable shell or cover forming top is adapted to be wrapped about a case or lunch box which is shown in Fig. 9 as including a light framework 5 of suitable dimensions and which may have fabric or other light side and end walls 6 and a pliable cover sheet 7. This lunch box is adapted to be placed upon one of the slats of the top which will serve therefore as a bottom, and to position the upright side walls formed by the slats 2, these are preferably provided with dowel pin holes 10 to receive dowel pins 11 which are provided in end panels or blocks 12 which, preferably, are provided with handles 13. It will be seen that the end panels 12 are therefore adapted to be locked by the dowel pins in register with the contiguous sections 2 of the top and form a receptacle or shell in which the lunch box structure, above mentioned, may be inclosed.

To utilize the flexible table top for table purposes, I provide a table stand which consists of a pair of cross pieces 15 of suitable length and which are provided in top faces with dowel pin apertures provided in the table top element 2. The cross pieces 15 are adapted to be snugly packed with the dowel pins of one entering dowel pin holes 17 of the other. These cross pieces 15 are adapt-

ed to be held in spaced parallel relation upon the upper ends of legs 20 of which there is a pair at each end of the stand, and each pair of legs is adapted to be folded from a crossing to a parallel position on respective pivot bolts 21 passing through the meeting portions of each leg 20 of a pair; the inner ends of the bolts being provided with wing nuts 22 which may be readily run off the bolts to provide for application of a longitudinal brace 23, which has adjacent each end a laterally projecting tongue 24 perforated to pass over the inwardly projecting end of the contiguous pivot bolt 21 after which the wing nuts are adapted to be set up.

The cross pieces 15 are provided with eyes 15^a on their inner edges to receive hooks provided on ends of brace links 25 which are pivoted at 26 to the longitudinal brace 23. Further bracing means consists of leg sections 28 which are provided with hinges 29 at upper ends. These hinges 29 are mounted on the pivot bolts 21; the hinges permitting the leg sections 28 to be folded down flatwise upon contiguous main legs 20 when the table stand is knocked down. The hinge leaf 29^a mounted on its bolt 21 is held from separation as by a clamp nut 30 provided on the bolt.

When the stand has been erected as is shown in Fig. 8, the supplementary leg sections 28 are adapted to be braced in inwardly extended oblique position as by brace hooks 32 which are pivotally connected to the leg sections 28 and are adapted to be hooked to the lower ends of the main legs 20.

To facilitate the substantial attachment of the upper ends of the legs 20 to the cross pieces 15, these latter are provided with recesses 15^b in their lower faces, and at one end of each of the recesses there is secured a suitable keeper or keyhole plate 35 of a length sufficiently less than the length of the recess 15^b to permit the application of the end of a leg 20 into the recess with a screw head 20^a in a position to be pushed into a keyhole 35^a in the plate 35, then when the head 20^a is shifted longitudinally of the keyhole plate it passes into the narrower part of the keyhole 35^a and the parts are thus firmly interlocked. The angular relation of the leg end 20 to the cross piece 15 is such that pressure down on the cross piece tends to spread the upper ends of the legs 20 and insure the efficient locking of the parts and prevent their accidental separation under pressure on the applied table top 2.

A further feature of the invention consists in providing means for the storage and arrangement of small utensils, and such provision is shown as consisting of elastic straps 38 secured to the inside faces of the

end panels 12, and under which straps there may be placed spoons, knives, forks and other culinary utensils, as may be desired. The end panels 12 are shown as spaced sufficiently behind the ends of the lunch box 5 to provide for such introduction of articles as may be desired to be held by the elastic retainers 38.

From the above it will be seen that I have provided a camp kit that may be compactly assembled in knock-down condition, and which can be readily unfolded and set up for use and made rigid and stable.

The box or case shown in Fig. 9 is preferably of collapsible form thus enabling the top frame to be folded down close to the bottom 5^a of the box, the fabric side walls 6 providing for this collapsing relatively. To hold the frame 5 in spaced box forming position, corner legs 5^b are hingedly connected as at 5^c to the bottom of the box, and these legs are, therefore, adapted to be swung downwardly and inwardly over the bottom 5^a after which the top frame 5 can be brought down in collapsed position.

Further embodiment, modifications and changes may be resorted to within the spirit of the invention as here claimed.

What is claimed is:

1. A collapsible camp table comprising, in combination, a table top forming element, and a collapsible table stand, said stand including cross pieces, and dowel means for securing the top element and the cross pieces, said dowel means including dowel pins in the cross pieces, each cross piece having dowel pin holes so that the cross pieces may be placed face to face with the dowel pins of each entering the other piece.

2. In a collapsible camp table, a table stand consisting of sets of pivotally connected legs, cross pieces attachable to the top ends of the legs when they are in diverging positions, a longitudinal brace for connecting the sets of legs, and supplementary bracing leg sections.

3. In a collapsible camp table, a table stand consisting of sets of pivotally connected legs, cross pieces attachable to the top ends of the legs when they are in diverging positions, a longitudinal brace for connecting the sets of legs, and supplementary bracing leg sections, the leg sections having pivot bolts to which the bracing leg sections are connected.

4. In a collapsible camp table, a table stand consisting of sets of pivotally connected legs, cross pieces attachable to the top ends of the legs when they are in diverging positions, a longitudinal brace for connecting the sets of legs, and supplementary bracing leg sections, the leg sections having pivot bolts to which the bracing leg

sections are connected, said bracing leg sections being foldable into parallel position with the collapsed legs.

5. In a collapsible camp table, a table stand consisting of sets of pivotally connected legs, cross pieces attachable to the top ends of the legs when they are in diverging positions, a longitudinal brace for

connecting the sets of legs, and supplementary bracing leg sections, the pivotal connection of the legs consisting of pivot bolts, said longitudinal brace being connectible to said bolts. 10

In testimony whereof I have signed my name to this specification.

M. M. LARSEN.
